COMBINATION BOX FOR STORING AND IMMERSING DENTURES

Ira W. Schwartz, Rose Vale, N.Y.

Application September 8, 1959, Serial No. 57,482

Term of patent 14 years

(Cl. D58—12)

Fig. 1.

Fig. 2.

Fig. 5.

Fig. 4.

Fig. 6.

The side not shown is the same as the side shown.

I claim:

The ornamental design for a combination box for storing and immersing dentures, as shown and described.
